(57) CLAIM

The ornamental design for a golf club stand, as shown and described.

DESCRIPTION

FIG. 1 is a perspective top front right view of the golf club stand, showing my new design;
FIG. 2 is a perspective top rear left view thereof;
FIG. 3 is a front elevation view thereof;
FIG. 4 is a rear elevation view thereof;
FIG. 5 is a right elevation view thereof;
FIG. 6 is a left elevation view thereof;
FIG. 7 is a top plan view thereof;
FIG. 8 is a bottom plan view thereof; and,
FIG. 9 is a perspective top rear left view thereof, where a pair of foot peg features are partially stored within a bottom tubular feature.

1 Claim, 6 Drawing Sheets
